UNITED STATES PATENT OFFICE.

ALFRED J. RIPLEY, OF LONG BRANCH, NEW JERSEY.

DESIGN FOR A PICTURE-FRAME.

SPECIFICATION forming part of Design No. 26,348, dated December 1, 1896.

Application filed October 27, 1896. Serial No. 610,232. Term of patent 3½ years.

To all whom it may concern:

Be it known that I, ALFRED J. RIPLEY, a citizen of the United States, residing at Long Branch, in the county of Monmouth and State of New Jersey, have invented and produced a new and original Design for a Picture-Frame, of which the following is a specification, reference being had to the accompanying drawing, forming a part thereof, which is a perspective view of a frame embodying the features of my design.

The design consists of a frame having a surface representing cloth decorated with playing-cards and chips and likewise a depression simulating a "kitty" opening. 15

I claim—

The design for a picture-frame herein shown and described.

ALFRED J. RIPLEY.
